UNITED STATES PATENT OFFICE

MUSTAFA I. HAKKY, OF GLENDALE, RHODE ISLAND

DESIGN FOR A LUBRICANT DISPLAY DEVICE

Application filed September 10, 1932. Serial No. 44,805. Term of patent 3½ years.

To all whom it may concern:

Be it known that I, MUSTAFA I. HAKKY, a citizen of the Republic of Turkey, residing at Glendale, in the county of Providence and State of Rhode Island, have invented a new, original, and ornamental Design for a Lubricant Display Device, of which the following is a specification, reference being had to the accompanying drawing, forming part thereof.

The figure is a perspective view of the lubricant display device showing my new design.

What I claim is:—

The ornamental design for a lubricant display device, substantially as shown.

In testimony whereof I have affixed my signature.

MUSTAFA I. HAKKY.
